ROTARY TILLER

John Peter Bagan, Portland, Oreg., assignor of
one-third to Anthony R. Wanasek, Marshfield,
Oreg.

Application August 9, 1944, Serial No. 548,706

10 Claims. (Cl. 97—41)

1

This invention relates to a machine adapted for use for plowing or tilling the soil, grading or levelling the ground, weeding, etc., and is more particularly concerned with the type of machine in which a spirally shaped cutter blade is rotated in contact with the earth surface to be worked, serving to cut, pick up, disintegrate and redeposit the surface layer of earth. Prior workers, recognizing the merits of such a machine have made many attempts to provide a practical embodiment thereof which is capable of operation by a relatively unskilled person under varying soil conditions. Many difficulties have been encountered and as a result no such machine has, up to the present time, attained general acceptance and widespread use.

A primary cause of the difficulties heretofore encountered in providing a practical machine of this sort has been the spiral cutter.

An object of my invention is to provide a spiral cutter which eliminates many of the difficulties heretofore encountered, such as the tendency of the machine to act as a conveyor, moving the earth laterally of the machine so as to produce ridges and furrows instead of a smooth flat tilled surface and the tendency of the machine to move laterally. A further object of my invention is to provide a simple, easily constructed, inexpensive, easily operated machine which is relatively free of parts likely to break or function improperly.

In general my machine consists of a simple frame carried on two wheels which supports the transverse rotary tiller and drive mechanism. Due to the fact that the rotary tiller of my invention is balanced so as to be relatively free of a tendency to move the earth laterally or itself to move laterally, it is unnecessary to provide special means, such as coulters, to hold the machine in line or to provide special means to deposit the earth lifted by the spiral blades in a smooth layer.

A machine embodying my invention and illustrative thereof is shown in the accompanying drawings, in which,

Fig. 1 is a top plan view of the machine,
Fig. 2 is an elevation of the rear of the machine,
Fig. 3 is an elevation of the left side of the machine,

Fig. 4 is an elevation of the right side of the machine showing the means for driving the rotary cutter,

Fig. 5 is a right end elevation of the rotary cutter,

2

Fig. 6 is a left end elevation of the rotary cutter,

Fig. 7 is a section on the line 7—7 of Fig. 2 and Figure 8 is a fragmentary rear view of the rotary cutter showing the overlapping of the blades.

Referring to the drawings, 1 is the platform of the machine which may be made of wood or metal. Attached to and forming a part of this platform and lending strength and rigidity to it are the angle irons 2 and 3. Angle iron 2, secured to the front edge of the platform, has one edge projecting downwardly several inches providing a baffle which catches earth thrown upwardly and forwardly by the rotary cutter. The angle iron 3 is secured to the platform 1 parallel to but spaced from the rear edge thereof and has one edge projecting upwardly. The draw frame which is illustrated as a simple V consists of the side members 4 and 5 bolted to the platform through the angle irons 2 and 3 and attached at their front ends to the draw plate 6. The ends of the platform carry the angle irons 7, 7' at the right end and 8, 8' at the left end. Angle irons 7 and 7' and angle irons 8 and 8' are bolted together through the platform with the edges of angle irons 7 and 8 projecting upwardly and the ends of angle irons 7' and 8' projecting downwardly providing vertical flat end surfaces to which are secured the end plates 9 and 10. End plate 9 carries the housing 11 and mounted on the housing 11 and on the end plate 10 are the vertically adjustable wheel supports 12 and 13 which, in the form illustrated, are designed to be operated by means of a crank (not shown) on rods 12' and 13'. Vertical adjustment of the wheels 14 and 15 determines the depth of penetration of the rotary cutter into the ground. Wheels 14 and 15 may be of any suitable type. The type illustrated having a relatively wide V-shaped tread is preferred.

The housing 11 contains a suitable number of meshed pinions such as three (16, 17 and 18), the uppermost of which, 16, rotates with the shaft 19 which extends through the bearing 20 carried by the plate 9 and the lowermost of which, 18, rotates with the shaft 22 which is keyed to the shaft 23 of the rotary cutter. The middle pinion 17 merely transmits motion from the pinion 16 to the pinion 18.

The drive shaft 19 preferably is driven at two or more selected speeds through the transmission 25 from the propeller shaft 26. Propeller shaft 26 extends forwardly and is provided with means (not shown) for attachment to a power

source such as a tractor of known type which may be coupled to the draw plate 6 to move the machine and has a power take-off adapted to be coupled to the shaft 26 to rotate it. The propeller shaft preferably is provided with the two universal joints only one of which, 27, is shown, the other being in front of the clutch 29 which is adapted to slip when excessive force is applied and thus to protect the rotary cutter and its drive mechanism against breakage. 30 is a disc mounted on the frame of the machine and set at an angle and adapted to engage the ground and cut a furrow or clear the way for the lower end of the housing 11. 31 is a dirt baffle hinged to the rear edge of the platform 1 and provided at its lower edge with the endwise adjustable levelling bar 32.

The rotary cutter, as stated above, comprises the shaft 23, one end of which is keyed to and driven by the shaft 22. The other end is rotatably supported by the bearing 33 carried by the end plate 10. The rotary cutter as illustrated in Figs. 5, 6 and 7 comprises four balanced cutter sections *a*, *b*, *c* and *d* mounted on the shaft 23. It is to be understood, however, that the invention is not limited to four such sections since any number thereof, i. e. one, two, three, four or more of such sections may be employed depending upon the length of rotary cutter desired. The cutter sections are identical and therefore only one need be described in detail. The diameter and length of each cutter section and the pitch of the spiral blades thereof may vary within wide limits depending upon the size of the machine and the kind of work to be done. For convenience I shall describe a cutter which I have found to be well adapted for plowing farmland of the types commonly used for growing corn, wheat and other grain crops, cotton, and vegetables such as potatoes. This cutter is made in sections 40 about 14 inches long and 14 inches in diameter and with four sections. Each section comprises four blade members in two groups. Two of the four blade members 34 and 35 constituting one group start at a line around the shaft at an angle of 180° from each other and extend spirally 180° around the shaft with equal pitch. The other two blade members 36 and 37 constituting the other group start at a line on the shaft adjacent the ends of blades 34 and 35 at an angle of 180° from each other but at an angle of about 90° from the ends of blades 34 and 35 and extend around the shaft 180° at the same pitch which is the reverse of the pitch of blades 34 and 35. The pitches of the blades are such that they tend to convey earth toward their adjacent ends as the cutter rotates in contact with the earth to be treated, that is, in the same angular direction as the wheels 14 and 15. As stated, the diameter of the cutter, that is the distance between the opposite edges of two blades at the points of their intersection with a plane perpendicular to the axis of the cutter may be, say, 14 inches and the length of each blade longitudinally of the shaft 7 inches, making the length of the cutter section 14 inches and the pitch of the blade equal to its diameter.

It is preferable slightly to overlap the adjacent ends of blades 34 and 35 and blades 36 and 37 as shown in Figure 8. The overlap, that is the distance, longitudinally of the shaft that blades 34 and 35 extend between blades 36 and 37 and vice versa may amount to an inch more or less. This overlapping is a desirable but optional feature. It has been found to relieve or distrib-

ute the strain on the free ends of the blades. The opposite ends of the blades are reinforced and supported by the flat knife members 38 and 39 which lie in planes perpendicular to the axis of the rotary cutter. Each blade 34, 35, 36 and 37 consists of a right helicoidal portion 40 adjacent and secured to the axle of the cutter and an oblique helicoidal portion 41 extending outwardly from the right helicoidal portion 40. The relative widths of the portions 40 and 41 may vary within wide limits, that is, the width of portion 40 may be equal to or greater than or less than the width of portion 41, but generally for soil tilling purposes the portion 41 is somewhat wider than the portion 40 in the ratio of 2 to 1 or greater. The angle between the two portions also may vary. Portion 40 is always perpendicular to the axis of the cutter, that is, it is always a right helicoid but the portion 41 may depart from the perpendicular to the axis of the cutter by an angle from say 10° to about 75°. An angle of about 30° between the line of intersection of the portion 41 with a plane which coincides with the axis of the cutter and a line in said plane which is perpendicular to the axis of the cutter generally is preferred for ordinary soil cultivation purposes. The two portions 40 and 41 of each blade may be integral or they may be made separate from each other and welded, riveted or bolted together. The blades may be cast or formed by working sheet metal. The tips of the blades may be rounded as shown at 42.

As stated, two, three or more cutter sections may be mounted end to end on the same shaft or axle. The adjacent blades of adjacent sections should then be set at an angle of 90° to each other on the shaft.

The described cutter construction has many advantages over rotary spiral cutters heretofore employed particularly in that it eliminates end thrust and tendency of the machine to swerve from a straight forward path and the corresponding tendency to transport earth laterally of the machine and produce ridges and valleys is eliminated. While there is some tendency to move the earth to the middle of each section no objectionable production of a ridge has been found to occur in practice. This probably is due to the fact that there are four blades operating on the ground near the center of each section and to the further fact that each section is too short to produce an objectionable ridge. The short sections also avoid the difficulty frequently encountered in plowing or tilling rough ground with a relatively long rotary spiral cutter. The ground rarely is so rough or uneven that the end thrust of the oppositely pitched blades of each section do not encounter enough earth substantially to balance each other. Moreover, the end thrust of any single pair of blades is so small that the machine is not caused to move laterally from its normal forward path. The cutter operates smoothly and generally maintains a uniform depth and consumes power quite uniformly except when it strikes some obstruction such as a root or stone and thus avoids excessive wear and breakage of the driving mechanism. The cutter generally remains clear of earth and masses of vegetation such as vines even under relatively adverse conditions such as spots of very wet ground and heavy growth of vines.

I have found it to be advantageous in some instances, although not essential, to include in the machine a clod breaker consisting of a row of teeth similar to the teeth of a harrow mounted

between the end plates 9 and 10 and extending downwardly and rearwardly in the principal path of the earth thrown rearwardly by the rotary cutter.

It will be noted that I have not provided coulters or other means for guiding the machine, i. e. for resisting any tendency of the machine to shift sidewise due to end thrust of the rotary cutter. The use of coulters is, of course, not excluded.

I have shown the wheels 14 and 15 as being adjustable vertically and have shown means for quickly or frequently adjusting the wheels when the machine is in motion. In many instances, however, I have found that very little wheel adjustment is necessary. A given adjustment may serve for an entire field being cultivated and may serve for all of the fields of a farm and for treatments (plowing, cultivating, etc.) at different seasons of the year. The provision of means for the adjustment of the wheels while the machine is in motion or the omission of all means for adjusting the wheels is, therefore, within the scope of my invention.

While I prefer to provide for operation of the rotary cutter at two or more speeds, it is to be understood that it is within the scope of my invention to omit this feature as well as the use of the slip clutch for protection of the cutter when it strikes an obstruction. Modification of the frame of the machine, the use of different kinds of wheels and the provision of suitable bearings, universal joints and oiling and greasing means therefor are, of course, all within the skill of a mechanic and are within the purview of my invention.

I claim:

1. A rotary spiral tiller comprising a frame, supporting wheels and draft means, a spiral cutter mounted for rotation on the frame in a position to engage the ground and means for driving the rotary cutter, said rotary cutter comprising at least one section having a central shaft and at least one pair of spiral blades mounted thereon in predominately non-overlapping relationship to each other longitudinally of the shaft and oppositely pitched to move material toward each other when the cutter is rotated so that the forward edges thereof move downwardly as the cutter is moved forwardly, each blade extending substantially 180° around the shaft and the adjacent ends of the blades being equally spaced circumferentially of the shaft and the adjacent ends of blades of opposite pitch alternating with each other around the shaft.

2. A rotary tiller as defined in claim 1 in which the cutter section comprises a central shaft, a first group of spiral blades of the same length and pitch mounted on the same portion of the shaft at equal angular distances from each other and a second group of blades of the same length and pitch mounted on the adjacent portion of the shaft at equal angular distances from each other, the number of blades in each group being equal and each blade of the first group being equally angularly spaced between two adjacent blades of the second group and the pitches of the two groups of blades being opposed to each other so that as the cutter rotates in contact with earth each group of blades will move earth toward the other group.

3. A rotary tiller as defined in claim 1 in which the cutter section comprises a central shaft, a first group of spiral blades of the same length and pitch mounted on the same portion of the

shaft at equal angular distances from each other and a second group of blades of the same length and pitch mounted on the adjacent portion of the shaft at equal angular distances from each other, the numbers of blades in each group being equal and each blade of the first group being equally angularly spaced between two adjacent blades of the second group and the pitches of the two groups of blades being opposed to each other so that the cutter rotates in contact with earth each group of blades will move earth toward the other group, and the adjacent ends of the blades of the two groups overlapping each other longitudinally of the shaft.

4. A rotary tiller as defined in claim 1 in which the cutter section comprises a central shaft, a first group of spiral blades of the same length and pitch mounted on the same portion of the shaft at equal angular distances from each other and a second group of blades of the same length and pitch mounted on the adjacent portion of the shaft at equal angular distances from each other, the numbers of blades in each group being equal and each blade of the first group being equally angularly spaced between two adjacent blades of the second group and the pitches of the two groups of blades being opposed to each other so that as the cutter rotates in contact with earth each group of blades will move earth toward the other group, each blade of each group of blades consisting of an inner right helicoidal portion and an outer oblique helicoidal portion.

5. A rotary tiller as defined in claim 1 in which the cutter section comprises a central shaft, a first group of spiral blades of the same length and pitch mounted on the same portion of the shaft at equal angular distances from each other and a second group of blades of the same length and pitch mounted on the adjacent portion of the shaft at equal angular distances from each other, the numbers of blades in each group being equal and each blade of the first group being equally angularly spaced between two adjacent blades of the second group and the pitches of the two groups of blades being opposed to each other so that as the cutter rotates in contact with earth each group of blades will move earth toward the other group, and flat knife members perpendicular to the central shaft and overlying the remote ends of the blades.

6. A rotary tiller as defined in claim 1 in which the cutter section comprises a central shaft, a first group of spiral blades of the same length and pitch mounted on the same portion of the shaft at equal angular distances from each other and a second group of blades of the same length and pitch mounted on the adjacent portion of the shaft at equal angular distances from each other, the numbers of blades in each group being equal and each blade of the first group being equally angularly spaced between two adjacent blades of the second group and the pitches of the two groups of blades being opposed to each other so that as the cutter rotates in contact with earth each group of blades will move earth toward the other group and the length of each blade longitudinally of the shaft being about equal to its radial dimension.

7. A rotary tiller comprising a frame, supporting wheels and draft means, a spiral cutter mounted on said frame for rotation in contact with the ground and means for rotating said cutter, said cutter comprising at least one section having a central shaft, a group of at least two blades of the same length and pitch mounted

on the same portion of the shaft and equally spaced from each other, a second group of at least two spiral blades of the same length and pitch mounted on the adjacent portion of the shaft and equally spaced from each other, the numbers of blades in each group being equal and the blades of one group being of the same size but of equal and opposite pitch to the blades of the other group, the adjacent ends of each group of blades overlapping each other longitudinally of the shaft and each blade of each group being equally spaced between two adjacent blades of the other group, each blade of each group consisting of an inner right helicoidal portion and an outer oblique helicoidal portion.

8. A rotary tiller as defined in claim 7 in which each section has four blades and the pitch of each blade is substantially equal to its outer diameter.

9. A spiral tiller as defined in claim 7 in which each section has four blades each of which encompasses about 180° of the circumference of the shaft and has a pitch substantially equal to its outer diameter.

10. A spiral tiller comprising a frame, supporting wheels and draft means, a spiral cutter mounted for rotation on said frame in contact with the ground and means for rotating the same in such a direction that the forward edges of the blades of the cutter move downwardly as the tiller 30

moves forwardly, said cutter comprising a horizontal shaft and a plurality of cutter sections each consisting of four spiral blades of equal length and pitch mounted on the shaft, the pitch of the blades being substantially equal to their outer diameters, each blade consisting of an inner right helicoidal portion and an outer oblique helicoidal portion, the latter being inclined at an acute angle with the shaft toward the direction that the spiral blades will move material when rotated in the direction defined, a pair of said blades being of the same pitch and equally spaced from each other on one portion of the shaft and a second pair of said blades being of the same pitch and equally spaced from each other on the adjacent portion of the shaft, the pitch of the first pair of blades being opposite to that of the second two blades so that each pair of blades tends to move material toward the other when the cutter is rotated in the direction specified, each blade being of such a pitch as to extend substantially 180° around the circumference of the shaft, the adjacent ends of each pair of blades overlapping each other along the shaft and being equally spaced around the shaft and the remote ends of each blade being supported by flat knife members lying in planes perpendicular to the shaft and covering said ends of the blades.

JOHN PETER BAGAN.
